HIGH FREQUENCY WAVE MODULATION

Manfred von Ardenne, Berlin, Germany, assignor
to Radioaktiengesellschaft D. S. Lowe, Berlin-
Steglitz, Germany, a company of Germany

Application November 23, 1931, Serial No. 576,850
In Germany November 22, 1930

5 Claims. (Cl. 250—17)

In the erection of a multiple radio system employing ultra-short waves, which are modulated with a plurality of high frequencies, certain difficulties are encountered insofar as it is a question of covering territories which are larger than the range, i. e., the optical range of the ultra-short waves. If, for example, a town of the size of Berlin is to be furnished with a multiple radio or television program, it is nevertheless to be expected, even if employing 9 metre waves and erecting the sender at an extremely elevated point, that perfect reception will not be possible in all suburbs.

Under these circumstances it is suggestive to suitably distribute 2 or 3 ultra-short wave senders over the area of the town in order to satisfy all subscribers. With an arrangement of this kind, however, there will be, more particularly in the central part of the town, large areas where the ultra-short waves arrive with approximately the same strengths of field. In order in these areas to separate the ultra-short waves a more or less considerable selection will be required dependent on the spacing of the waves.

25 The present invention deals with the question of utilizing the selective properties of normal radio receivers for separating a plurality of ultra-short wave senders, and thus avoiding the necessity of providing particularly effective selecting means in the requisite ultra-short wave auxiliary apparatus.

Fundamentally, these difficulties may be avoided by modulating different high frequencies on to the different ultra-short wave transmitters, 35 all of which frequencies, however, are preferably included within the range of one octave. If the ultra-short wave senders were each modulated with 3 high frequencies, each high frequency is modulated by a program, (it may also be the same three programs), the different high frequencies, according to the additional subject matter of the invention, are intended to be distributed in such fashion over the available interval, for example 300-600 m., that even in the 40 case when the different ultra-short wave senders are demodulated simultaneously by a simple, non-selective auxiliary apparatus, there are no disturbances, or merely a minimum thereof. This is the case if the high frequencies are distributed evenly over the wave range.

In this connection it is to be observed that the octave requires to be precluded, i. e., that the waves λ to be selected require to comply with the condition $\lambda_1 \leq \lambda < 2\lambda_1$, whereby λ_1 represents 55 the lower wave length limit.

Disturbances may also occur in connection with multiple broadcasting of this nature over the plurality of ultra-short wave transmitters when the deviations of the ultra-waves reach such a level that the resultant difference frequencies fall within the high frequency range employed, for example 300-600 m.

If, for example, it is desired to transmit three programs, and three ultra-short wave senders are to be employed for influencing the receivers, 65 there are preferably selected for the three programs more particularly nine different wave lengths, which are preferably disposed within the selected octave with equal but greatest possible frequency spacing. If then the waves 70 $\lambda_1, \lambda_2, \lambda_3, \lambda_4$ etc. are in the order of the range of their wave lengths, the ultra-short wave transmitters S_1, S_2, S_3 will preferably be so modulated that one ultra-short wave transmitter is modulated by the waves $\lambda_1, \lambda_4, \lambda_7$, the second by 75 $\lambda_2, \lambda_5, \lambda_8$, and the third by the waves $\lambda_3, \lambda_6, \lambda_9$. The three programs are then preferably distributed in such fashion over the single waves that the one program is carried by the waves λ_1, λ_2 and 80 λ_3 , the second by the waves λ_4, λ_5 and λ_6 , and the third by the waves λ_7, λ_8 and λ_9 .

As already stated above, the invention may be employed not only in respect of speech or tone modulated high frequencies, but also for high frequency bands, such as are frequently used, for example, in connection with television. The high frequency bands are then preferably transferred in unitary fashion either to the higher or to the lower parts of the high frequency range to be transmitted.

The invention is illustrated diagrammatically in Figs. 1 and 2.

In Fig. 1 the high frequency generators the waves of which are to be transmitted are designated $\lambda_1, \lambda_2, \lambda_3, \lambda_4, \lambda_5, \lambda_6, \lambda_7, \lambda_8, \lambda_9$, viz., in the order of their wave lengths. S_1, S_2, S_3 are three ultra-short wave transmitters, which are controlled by the high frequency generators λ_1, λ_4 and 90 $\lambda_7, \lambda_2, \lambda_5$ and λ_8 , and λ_3, λ_6 and λ_9 respectively.

Fig. 2 shows a possible form of embodiment of 100 a transmission system of this nature. It is assumed, for example, that the oscillatory circuits 1 and 2 of the transmission tubes oscillate in the frequencies λ_2, λ_5 and λ_8 . The three generators are modulated according to one of the known 105 modulation systems, for example according to the principle of the parallel tube control. The parallel tubes 4 are controlled by a microphone 6 or similar elements through the medium of a repeater 5, and thus modulate the high frequency 110.

generator. The three high frequency generators λ_2 , λ_5 and λ_8 control through the medium of coupling coils 7 a modulating valve 8, which is situated in the grid circuit of the short-wave 5 transmitter tube 9. In the anode circuit of this tube, which is connected for self-excitation, there is an oscillatory circuit 10, which passes the modulated ultra-short wave energy to the radiating system (aerial 11). 12 are the various heating 10 batteries, 13 the anode batteries, 14 the initial grid voltage batteries and 15 the microphone batteries. 16 are the high frequency and 17 the low frequency chokes.

As already mentioned above, it is naturally 15 also possible to employ both other forms of ultra-short wave transmission systems as well as other high frequency generator systems, and also in the case of both systems to provide other forms of modulation. The transmission of the modulated 20 high frequency oscillation to the ultra-short wave transmitter may also be performed in various different manners, dependent on the fact as to whether the high frequency generators are situated at or away from the transmitter. In the 25 case of distant transmission it is of course necessary to conduct the high frequency energy of the oscillatory circuit 2 to an aerial system, to receive the radiated energy, and to amplify the same or pass it to the coil 7.

30 I claim:

1. In an arrangement for transmitting one or more programs, two or more ultra-short wave transmitters, means for generating several groups of intermediate frequencies, means for modulating each of said groups by the same program, each of said ultra-short wave transmitters being modulated by one intermediate frequency of each of said several groups of intermediate frequencies.

40 2. In an arrangement for transmitting one or more programs, two or more ultra-short wave transmitters, means for generating several groups of intermediate frequencies, means for modulating each of said groups by the same program, each of said ultra-short wave transmitters being modulated by one intermediate frequency of each of said several groups of intermediate frequencies.

45

50 frequencies, the frequencies of said ultra-short wave transmitters differing from each other to such extent, that the difference frequencies are situated outside the range of the modulating high frequency bands.

55 3. In an arrangement for transmitting one or more programs, two or more ultra-short wave transmitters, means for generating several groups of intermediate frequencies, means for modulating each of said groups by the same program, each of said ultra-short wave transmitters being modulated by one intermediate frequency of each of said several groups of intermediate frequencies, said groups of intermediate frequencies, limited to and distributed over the range of a single octave, whereby the wave, corresponding 60 with the octave, remains unemployed.

65 4. In an arrangement for transmitting one or more programs, two or more ultra-short wave transmitters, means for generating several groups of intermediate frequencies, means for modulating each of said groups by the same program, each of said ultra-short wave transmitters being modulated by one intermediate frequency of each of said several groups of intermediate frequencies, said intermediate frequencies distributed 70 to said groups in such a manner that the intermediate frequencies in each group, for transmitting the same program, differing from each other to the greatest possible extent.

75 5. In an arrangement for transmitting one or more programs, two or more ultra-short wave transmitters, means for generating several groups of intermediate frequencies, means for modulating each of said groups by the same program, the intermediate frequencies modulated by the same program being the nearest to each other, each of said ultra-short wave transmitters being modulated by one intermediate frequency of each of said several groups of intermediate frequencies, said intermediate frequencies distributed 80 to said groups in such a manner that the intermediate frequencies in each group, for transmitting the same program, differing from each other to the greatest possible extent.
